[57] **CLAIM**

The ornamental design for a combined nursing bottle support and holder, substantially as shown and described.

DESCRIPTION

FIG. 1 is an elevational view of one side of a combined nursing bottle support and holder showing my new design;

FIG. 2 is an elevational view of the opposite side of the design shown in FIG. 1;

FIG. 3 is a front elevational view of the design shown in FIG. 1;

FIG. 4 is a rear elevational view of the design shown in FIG. 1;

FIG. 5 is a top plan view of the design shown in FIG. 1; and

FIG. 6 is a bottom plan view of the design shown in FIG. 1.
